ENGINEER ARCHITECT SCALE

Wesley Dale Weeks and Ludwig Kube, Phillips,
Tex.; said Kube assignor to said Weeks

Application September 27, 1944, Serial No. 556,032

3 Claims. (Cl. 33—107)

The invention relates to a changeable scale rule, and more especially to changeable triangular rule.

The primary object of the invention is the provision of a rule of this character, wherein it has nested reversible scale blades, adapting these for immediate use by engineers, draftsmen, architects or others, the rule being a combination instrument, and is compact, so that it can be conveniently transported, stored in the least possible space, and is handy for the purposes intended thereof.

Another object of the invention is the provision of a rule of this character, wherein there is involved the grouping of different scale blades, which are reversibly connected together for selected use with dispatch and convenience.

A further object of the invention is the provision of a rule of this character, wherein the scale blades are hinged to each other in a novel and unique manner, so that a selected blade can be promptly brought into a working position, without interference by the other non-working blades, and all of such blades are held in a fixed relation to one another, either in a working or non-working position.

A still further object of the invention is the provision of a rule of this character, which is simple in construction, thoroughly reliable and efficient in operation, strong, durable, readily and easily adjusted, changeable with dispatch, conveniently operated, and inexpensive to manufacture.

With these and other objects in view, the invention consists in the features of construction, combination and arrangement of parts as will be hereinafter more fully described in detail, illustrated in the accompanying drawings, which show the preferred embodiment of the invention, and pointed out in the claims hereunto appended.

In the accompanying drawings:

Figure 1 is a fragmentary elevation of the rule constructed in accordance with the invention portions of its scale blades extended.

Figure 2 is a vertical cross sectional view through the rule, the blades by full lines being shown folded relative to each other and by dotted lines unfolded.

Figure 3 is a sectional view taken on the line 3—3 of Figure 2 looking in the direction of the arrows, an arrow being indicated therewith for showing the direction of folding and unfolding movements of the blades.

Figure 4 is a fragmentary longitudinal sectional view through the rule at its capped end. 55

Figure 5 is a fragmentary plan view of the capped end shown in Figure 4.

Figure 6 is a sectional view taken on the line 6—6 of Figure 4 looking in the direction of the arrows.

Figure 7 is a perspective view of the end cap looking toward its outer face.

Figure 8 is a view similar to Figure 7 looking toward its inner face.

Figure 9 is a perspective view, partly broken away, showing the blades arranged for the use of the rule as an architect's scale.

Figure 10 is a view similar to Figure 9 showing the rule changed for use as an engineer's scale.

Figure 11 is a vertical transverse sectional view showing in detail the hinge connections between the blades, such being a modification over that shown in Figure 3.

Figure 12 is a sectional view taken on the line 12—12 of Figure 11 looking in the direction of arrows.

Similar reference characters indicate corresponding parts throughout the several views in the drawings.

Referring to the drawings in detail, A designates generally the scale rule constructed in accordance with the invention, and comprises a series of three ruling blades 10, 11, and 12, respectively, each having on one face an architect's graduated scale markings 13, while on the opposite face are the engineer's graduated scale markings 14. It is designed that the architect's scale markings 13 of all of the blades 10, 11 and 12, be visible at one and the same time, this being also true with respect to the engineer's scale markings 14 and to accomplish this, the ends of the blades adjacent to each other are swingably connected by hinges 15 to a substantially triangular shaped end cap 16, the latter being formed at the straight edges 17 thereof with hinge pintles 18 about which the strap hinges 15 are loosely looped, so that the blades 10, 11 and 12, can be swingingly folded or unfolded for reversing the same to bring the architect or engineer's scale markings into view and in a position for use in the order of triangular relationship to each other, as best seen in Figures 9 and 10 of the drawings.

To hold the blades 10, 11 and 12, in the triangularly related reversed positions with respect to each other, there is provided a removable substantially triangular shaped latching cap or end head 19, which at the marginal edges thereof is formed with counterseats 20 for the ends of the blades to be engaged by this cap or head for fric-

tional hold thereon, as best seen in Figures 5, 6, 7 and 8 of the drawings. The cap or head 19 is telescoped onto the ends of the blades 10, 11 and 12 thereof to maintain the said blades in nest triangular nested relation, one to the other. In this relationship, the scale markings 13 or 14 will be visibly exposed outermost for the reading or using thereof, optionally.

The cap or head 19 is formed with the resilient releasing lips or tongues 20, which overly the outer faces of the blades 10, 11 and 12, when such cap or head is engaged on the latter.

In Figures 11 and 12, of the drawings, there is shown a slight modification, wherein the cap or head 21 carries the hinge straps 22 which are loosely looped about the hinge pintles 23 formed on the ends next to this cap or head 21 of the blades 24, the latter being identical to the blades 10, 11 and 12, with respect to the scale markings, with this exception.

What is claimed is:

1. A rule of the kind described, comprising a plurality of blades having scale markings on the inside and outside faces thereof, an end cap hingedly connected to the blades for the reverse swinging of the latter into reverse triangular relation to each other, and a second end cap en-

gageable with the other ends of said blades to latch the same in their triangular relation to one another.

2. A rule of the kind described, comprising a plurality of blades having scale markings on the inside and outside faces thereof, an end cap hingedly connected to the blades for the reverse swinging of the latter into reverse triangular relation to each other, a second end cap engageable with the other ends of said blades to latch the same in their triangular relation to one another and counterseats formed in the second end cap of receiving the ends of the blades therein.

3. A rule of the kind described, comprising a plurality of blades having scale markings on the inside and outside faces thereof, an end cap hingedly connected to the blades for the reverse swinging of the latter into reverse triangular relation to each other, a second end cap engageable with the other ends of said blades to latch the same in their triangular relation to one another, counterseats formed in the second end cap of receiving the ends of the blades therein and lips on the second end cap.
